MECHANISM FOR WATER-MARKING PAPER

Howard Brown, Longmeadow, Mass., assignor to
Southworth Company, West Springfield, Mass.,
a corporation of Massachusetts

Application February 15, 1932. Serial No. 592,910

5 Claims. (Cl. 92—48)

This invention relates to paper-making machines and particularly to mechanism for applying water-marks to the paper as it is produced in such machines.

5 One object of my invention is to provide improved and readily accessible means for bringing the water-marking roll into exact parallel relation with the associated bottom roll, together with improved means for simultaneously adjusting both ends of the water-marking roll toward and away from the bottom roll to effect the desired impression of the water-marking plates on the partly-formed paper as it passes between the rolls.

15 Another object of my invention is to provide means by which the water-marking roll may be conveniently adjusted axially, together with means for positively driving the roll in every axial position thereof.

20 My invention further relates to arrangements and combinations of parts which will be hereinafter described and more particularly pointed out in the appended claims.

A preferred form of the invention is shown in 25 the drawing, in which

Fig. 1 is an end elevation of parts of a paper-making machine embodying my improvements;

Fig. 2 is a front view thereof, looking in the direction of the arrow 2 in Fig. 1, and

30 Figs. 3 and 4 are detail sectional views, taken along the lines 3—3 and 4—4 respectively in Fig. 1.

Referring to the drawing, I have shown a frame 10 on which a bottom roll 11 is rotatably supported in stands or brackets 12. Any suitable means (not shown) may be provided for rotating the bottom roll 11.

40 A water-marking roll 15 is mounted above the bottom roll 11 and is rotatable in bearings 16 in arms 17 pivoted at 18 to the stands or brackets 12.

Nuts 20 are swiveled in the outer ends of the arms 17. Front and rear elevating screws 22 and 23 are threaded in the nuts 20 and extend down-

45 ward through openings 24 (Fig. 2) in the frame 10. Worm gears 26 and 27 are mounted on the elevating screws 22 and 23, and the lower ends of the hubs of the worm gears 26 and 27 engage the upper surface of the frame 10, as shown in

50 Fig. 2, and thus definitely limit downward movement of the screws and worm gears.

Pressure levers 30 are pivoted at 31 to the frame 10 and are provided with slots 32 through which the reduced lower end portions 33 of the 55 screws 22 and 23 extend. Collars 34 are secured

to the end portions 33 below the levers 30. Weights W are mounted on the levers 30 and may be secured in adjusted position thereon by binding screws 36. The weighted levers 30 apply yielding pressure to the water-marking roll 15 during the operation of the machine.

A sleeve 40 (Fig. 3) is rotatable in fixed bearings 41 on the frame 10 and is provided with a hand wheel 42 at one end, a worm 44 between the bearings 41, and a collar 45 secured to the sleeve 65 40 at the end thereof opposite to the hand wheel 42. The worm 44 engages the worm-gear 26 previously described and constitutes means for turning the front elevating screw 22 to adjust the front bearing 16 of the water-marking roll 15. 70

A shaft 50 extends loosely through the sleeve 40 and also through bearings 51 (Fig. 1) at the rear side of the machine. The shaft 50 is provided with a hand wheel 52 at the front end thereof and with a worm 54 mounted between 75 the bearings 51 and engaging the worm gear 27 on the rear elevating screw 23.

With this adjusting mechanism, the bearings 16 at each end of the water-marking roll 15 may be raised or lowered and may be separately adjusted as desired to bring the water-marking roll 15 into exact parallel relation to the bottom roll 11.

When the desired parallel relation has been attained, a set screw or other locking device 60 (Fig. 3) may be tightened to connect the hand wheel 42 and sleeve 40 to the shaft 50, so that the worms 44 and 54 may be turned simultaneously by use of the hand wheel 52. It is then possible to raise or lower the water-marking roll 15 without disturbing its parallel relation to the bottom roll 11.

I have thus provided very convenient mechanism by which the operator standing at the front of the machine is enabled to separately raise or lower either the front or rear bearing of the water-marking roll or to simultaneously raise or lower both bearings to change the spacing between the rolls 11 and 15.

This arrangement constitutes a substantial improvement over the previous practice, in which it was necessary to adjust the front bearing from the front of the machine and to adjust the rear bearing from the rear of the machine, and in which no simultaneous adjustment of the front and rear bearings was possible. A great deal of time and labor is thus saved, particularly when changing over from one water-marking roll to another or from one thickness of paper to another.

I have also provided improved means for adjusting the water-marking roll 15 axially. For this purpose a member 70 is loosely mounted in a groove or recess in the forward end of the shaft 71 of the water-marking roll 15. This member 70 (Fig. 4) is threaded to receive an adjusting screw 72 rotatable at its rear end in a fixed bearing 73 and held from axial movement therein by a shoulder 74 and collar 75. A hand wheel 76 is provided at the front end of the screw 72, by which the screw may be turned to adjust the member 70 and the water-marking roll 15 axially of the roll.

The shaft 71 is preferably provided at its rear end with a gear 80 engaging a wide face gear 81 on the shaft 82 of the bottom roll 11. A positive gear drive is thus provided between the rolls 11 and 15 in every axial position of the water-marking roll. Consequently the water-marking plates M may be readily shifted axially to bring them into desired alignment with the edges of the paper P. It is unnecessary to re-adjust the driving gears, as they are at all times in driving relation.

I have thus provided mechanism for adjusting the water-marking roll vertically or axially in such manner that the operation of the machine is facilitated. Accurate setting of the water-marking plates is much more quickly and easily accomplished in my improved machine.

Having thus described my invention and the advantages thereof, I do not wish to be limited to the details herein disclosed, otherwise than as set forth in the claims, but what I claim is:—

1. In a paper-making machine, a bottom roll, a water-marking roll, bearings for the two ends of said water-marking roll, pivoted arms supporting said bearings, elevating screws connected to the swinging outer ends of said arms, a horizontal shaft connected to turn one of said elevating screws, a sleeve loose on said shaft and connected to turn the other elevating screw, separate manual means located at one side of the machine for turning said shaft and said sleeve, and means to connect said shaft and sleeve for simultaneous movement.

2. In a paper-making machine, a bottom roll, a

water-marking roll, bearings for the two ends of said water-marking roll, pivoted arms supporting said bearings, elevating screws connected to the swinging outer ends of said arms, a horizontal shaft connected to turn one of said elevating screws, a sleeve loose on said shaft and connected to turn the other screw, and hand wheels on said shaft and sleeve and located at one side of the machine by which they may be separately rotated.

3. In a paper-making machine, a bottom roll, a water-marking roll, bearings for the two ends of said water-marking roll, pivoted arms supporting said bearings, elevating screws connected to the swinging outer ends of said arms, means to turn said screws, means to limit downward movement of said screws, levers connected to the lower ends of said elevating screws, and weights to tension said levers, said weights being adjustable on said levers to vary the pressure on the water-marking roll.

4. In a paper-making machine, a bottom roll, a water-marking roll, a single member loose on said water-marking roll but held from relative axial movement thereon, a single adjusting screw threaded into said member, means to hold said screw from axial movement in said machine, manual means by which said screw may be rotated to positively adjust said water-marking roll axially in either direction relative to said bottom roll and to retain said roll in adjusted position, and a positive driving connection between said rolls operative in every axially adjusted position of said water-marking roll.

5. In a paper-making machine, a bottom roll, a water-marking roll, bearings for the two ends of said water-marking roll, devices effective to separately raise and lower each of said bearings of said water-marking roll, separate manual means located at one and the same side of the machine and by which either one of said devices may be separately actuated from a single operating position, and means to couple said devices together for raising and lowering both of said bearings of said water-marking roll simultaneously and equally and from the same operating position.

HOWARD BROWN.
